GRADING MACHINE

Albert R. Henry, Salina, Kans., and Marion C. Wills, Kansas City, Mo.

Application December 16, 1938, Serial No. 246,146

2 Claims. (Cl. 37—156)

Our invention relates to improvements in grading machines of a type in which a draw bar, oscillatively connected to a traveling frame, rotatively supports a circle which carries a scraper.

5 One of the objects of our invention is the provision of novel means for rotating the circle, which means is simple, cheap to install and in upkeep, which is strong, and not likely to get out of order, which is easily operated and enables the 10 employment of a minimum of power for a maximum of power effect, and which is efficient in its operation.

The novel features of our invention are hereinafter fully described and claimed.

15 In the accompanying drawings which illustrate our invention,

Fig. 1 is a perspective view of a grading machine of the kind referred to provided with one form of our improvement which embodies a 20 motor having a driving worm engaging a peripherally toothed circle, parts being omitted.

Fig. 2 is a plan view of the circle and draw bar of the machine including the improvement shown in Fig. 1.

25 Fig. 3 is an enlarged view of the motor partly in end elevation, partly in vertical section, and partly broken away.

Fig. 4 is a side elevation, partly broken away of what is shown in Fig. 2.

30 Fig. 5 is an enlarged transverse vertical sectional view of the draw bar, the circle and adjacent parts, some parts being shown in elevation.

Fig. 6 is a plan view of the draw bar and 35 circle associated with a modified form of our invention, in which the motor is provided with a driving member having peripheral gear teeth engaging with peripheral teeth on the circle, parts of the apparatus being broken away.

40 Fig. 7 is a side elevation, partly broken away, of what is shown in Fig. 6.

Fig. 8 is a plan view of the draw bar and circle associated with a modification of our improvement in which the motor has a driving member 45 provided with sprocket teeth engaging a sprocket chain which forms an integral peripheral part of the circle, parts of the hydraulic circuit being omitted, and partly broken away.

Fig. 9 is a side elevation, partly broken away, 50 of what is shown in Fig. 8.

Fig. 10 is a diagrammatic view of the hydraulic circuit which includes the circle operating motor.

Fig. 11 is an enlarged longitudinal sectional view of the by pass valve and parts connected 55 therewith.

Similar characters of reference designate similar parts in the different views.

1 designates a traveling frame of usual construction carrying a cab 2, and supported upon carrying wheels 3.

4 designates a usual form of draw bar the forward end of which is provided with a ring 5 engaging the eye 6 of an eye bolt 7 mounted in the frame 1, whereby the draw bar is oscillative laterally and vertically.

8 designates the usual circle centrally pivoted by a bolt 9 to a cross bar 10 of the draw bar so as to be adapted for rotatable adjustment on the bolt 9.

11 designates a scraper of usual structure at 15 the rear of the circle 8 and attached rigidly thereto by two forwardly extending arms 12, whereby the scraper is rotatably adjusted with the circle. 13, Fig. 5, are lugs fastened to the under side of the bar 10 and engaging the under 20 side of an annular top flange of the circle 8.

For rotatably adjusting the circle 8 on the draw bar 4, so as to laterally swing the scraper 11, in the form of our invention shown in Figs. 1 to 5, the circle 8 has integral with it driven means 25 comprising an arcuate row of gear teeth 14 disposed circumferentially on the periphery of the circle 8 and in driving engagement with a worm 15 provided on the driving member, constituting a rotary shaft 16, of a rotary piston 17, 30 Fig. 3, rotatably mounted in an eccentric position in a casing 18 of a hydraulic motor.

The casing 18 is provided with two peripheral ports 19 and 20 communicating with a circular chamber 21 within which the piston 17 is eccentrically rotatably mounted and adapted for rotation in opposite directions.

The piston 17 has its periphery closely adjacent to the circular wall of the chamber 21 at a point midway between the ports 19 and 20.

The piston 17 is provided with radial recesses 22 in which are respectively slidably fitted blades 23, which are normally forced outwardly, so as to have traveling engagement with the circular wall of the chamber 21, by coil springs 24 respectively mounted in the recesses 22 and bearing at their inner ends against the piston 17, and bearing at their outer ends against the inner ends respectively of the blades 23, Fig. 3.

When liquid under pressure is forced into the chamber 24 through the port 19, Fig. 3, the liquid, such as oil, will engage successively the blades 23 and effect revolution counterclockwise of the piston 17 and the driving shaft 16, as viewed in 55

Fig. 3. The oil will pass from the chamber through the port 20.

When the oil is forced into the chamber 21 through the port 20, the piston 17 will be revolved with the shaft 16 in a clockwise direction, as viewed in Fig. 3, and the oil will pass out through the port 19.

As the shaft 16 and its worm 15 are rotated, the worm 15 will have traveling driving engagement with the teeth 14, thereby rotating the circle 8 and with it the scraper 11. Reversing the rotation of the shaft 16 will effect reversal of rotation of the circle 8.

The under side of the draw bar 4 has rigidly attached to it a bracket 25 which supports the casing 18 of the motor and serves as bearing means for the shaft 16 outside the casing 18.

In the form of our invention shown in Figs. 6 and 7, the construction corresponds to that shown in Figs. 1 to 5, with the following exceptions and differences. The casing 18 is mounted on a horizontal plate 26 secured rigidly to the underside of the draw bar 4, with the shaft 16 disposed parallel with the axis of the circle 8, while in the form shown in Figs. 1 to 5, the shaft 16 is transverse to the axis of the circle. A spur gear wheel 27 is rigidly attached to and revolves with the shaft 16 and meshes and has traveling engagement with the teeth 14 of the circle. In operation, when the shaft 16 is rotated with the gear wheel 27, the latter will rotate the circle 8 and with it the scraper 11.

In the form of our invention shown in Figs. 8 and 9, the construction corresponds to that shown in Figs. 6 and 7, excepting that the shaft 16 is provided with a sprocket wheel 28 which revolves with the shaft 16 and has traveling engagement with a sprocket chain 29 the ends of which are rigidly attached to the periphery of the circle 8 at points circumferentially apart, the sprocket wheel 28 being disposed between the chain 29 and the periphery of the circle 8. When the shaft 16 is rotated with the sprocket wheel 28, the latter will through the chain 29 rotate the circle 8 and with it the scraper 11.

By connecting the motor shaft directly to the circle, a driving connection between the motor and the circle is obtained with a minimum of parts, thus making the installation and upkeep at a minimum cost.

The term "integral" as applied herein to the teeth 14 and the chain 29 is used in its sense of making a part of the whole circle.

When the motor employed is of the hydraulic type, as shown in the drawings, it forms part of an hydraulic circuit which is shown diagrammatically in Fig. 10. Such circuit comprises the following described parts.

30 which designates a rotary pump of any usual construction, and which may correspond in structure to the motor shown in Fig. 3, has its outlet 31 communicating with piping 32 connected to an oil tank 33 which may be supported at any desired place on the machine, and which is connected by piping 34 to a port 35 of a controlling valve casing 36, which may be located in the cabinet 2 for convenience of operation therefrom.

The port 19 of the motor is connected to a piping 37 which is connected with a port 38 in the casing 36. The port 20 of the motor is connected by piping 39 with a port 40 in the casing 36. The intake 41 of the pump 30 is connected by piping 42 with a port 43 in the valve casing 36.

A valve 44 rotatable in the casing 36 is provided at one end with an operating handle 45. It is

provided therethrough with two transverse passages 46 and 47, each of which is adapted to have its ends respectively communicating with any adjacent two ports in the casing while the other passage has its ends communicating with the other two ports.

With the valve 44 disposed, as shown in solid lines in Fig. 10, the ports 38 and 43 connected by the passage 46, and the passage 47 connecting the ports 35 and 40, the propelling liquid will pass from the outlet 31 of the pump 30 through the piping 32 to the supply and pressure tank 33, thence through the piping 34, passage 47, piping 39 and port 20 into the motor chamber in the casing 18. The pressure of the liquid in the chamber 21 of the motor operating on the blades 23 will revolve the piston 17 and its shaft 16 clockwise, as viewed in Figs. 3 and 10, thereby effecting revolving of the worm 15, gear 27 or sprocket wheel 28, as the case may be, in one direction, and turning the circle 8 and the scraper 11 in one direction.

The propelling liquid passes from the casing 18 through the port 19, piping 37, passage 46, piping 42 and intake port 41 into the pump 30, thus completing the cycle.

If it is desired to reverse the direction of revolution of the driving shaft 16, the valve 44 is turned to the position shown in dotted lines in Fig. 10, in which position the passage 46 will connect with the ports 40 and 43, and the passage 47 will connect with the ports 35 and 38 of the valve casing 36.

The liquid will now pass from the pump 30 through the piping 32, tank 33, piping 34, passage 35 47, piping 37 and port 19 into the motor casing 18, thence to the port 20 and through the piping 39, passage 46 and piping 42 to the intake 41 of the pump 30, effecting, in its passage through the motor revolution of the piston 17 and driving shaft 16 counter-clockwise, as viewed in Figs. 10 and 3.

To prevent too high a pressure building up in the circuit, a by-pass connects the piping 32 and 42, such by-pass comprising a pipe 48 connected to the piping 32 and communicating with a chamber 49 in a valve casing 50, which has a passage 51 that connects the chamber 49 with a chamber 52, that in turn communicates with a pipe 53 connected to the piping 42.

The chamber 52 has aligned with the passage 51 a threaded opening in which is adjustably removably fitted a screw plug 54 having extending from its inner end and aligned with the passage 51 a recess 55, in which is slidably fitted the stem 56 of a valve 57. A coil spring 58 encircling the stem 56 bears at one end against the plug 54 and at its other end against the valve 57, thus normally holding the valve 57 in a seat provided at the adjacent end of the passage 51.

When the pressure in the piping 32, tank 33, piping 34 and piping 37 or 39 at the time connected therewith, reaches a predetermined amount, the pressure in the chamber 49 will open the valve 57, so that fluid will flow from the piping 32 through the pipe 48, chamber 49, passage 51, chamber 52, pipe 53 and piping 42 to the intake 41 of the pump 30, thus eliminating liability of damage to the circuit from too high a pressure caused by stoppage or over loading the motor.

The pump 30 may be located at any desired place on the machine, and the piping connections therewith and with the motor 18, such as the piping 37 and 39, may be hose or other flexible tubing.

With the parts constructed and arranged as

shown, when the valve 44 is in the position shown in dotted lines in Fig. 10, and the pump 30 is operated to discharge through the piping 32, the circle 8 will be revolved clockwise in the forms shown in Figs. 2 and 8. In the form shown in Fig. 6, with the valve in the position shown in solid lines in Fig. 10, the circle 8 will be revolved counterclockwise. By setting the valve 44 in the position shown in dotted lines in Fig. 10, the circle 10 in Figs. 2 and 8 will be revolved counterclockwise, and the circle 8 in Fig. 6 will be revolved clockwise.

By setting the valve 44 in neutral, that is with the passages 46 and 47 disconnected from the ports 35, 38, 40 and 43, the motor 18 will be disconnected, and will not be revolved in either direction, although the pump 30 is in operation. This would be the normal position of the valve 44, with the motor inoperative, excepting at such times as it is desired to shift the scraper 11. At such times, the operator sets the valve 44 in the proper position for having the motor 18 revolve the circle 8 to shift the scraper 11 to the desired position. In each of the three forms of our invention, shown in Figs. 2, 7 and 9, the driving member, constituting the shaft 16, is connected with the driven means on the periphery of the circle 8 by speed reducing means, as the worm 15 meshing with the teeth 14 of the circle 8, Fig. 2; the spur gear wheel 21, meshing with the teeth 14 of the circle 8, in Fig. 7; and the sprocket wheel 28 engaging the sprocket chain 29, in Fig. 9.

In each of these forms of our invention, the driving member 16 of the motor is thus connected with the circle 8 by speed reducing means which has traveling driving engagement with the driven means of the circle 8. This construction enables the use of a small cheap motor for rotating the heavy circle and the scraper in making the desired adjustments of the circle and scraper.

In making a substantial adjustment of the circle, the driving motor shaft 16 will make several continuous rotations in one direction, while the circle turns less than one fourth of a revolution.

Other modifications, within the scope of the 5 appended claims, may be made without departing from the spirit of our invention.

What we claim is:

1. In a grading machine having a traveling frame, a draw bar attached to and drawn by said frame, a circle rotative in either direction on said draw bar, and a scraper attached to and revoluble with said circle, in combination with a motor on said draw bar and having a drive shaft and means operated by pressure liquid for rotating said shaft 10 in either direction, liquid supply means for said motor by which pressure liquid can be caused to operate said shaft rotating means to rotate said shaft in either direction or hold said shaft from rotation, and speed reducing driving means connecting said drive shaft and said circle by which said circle is rotated at a speed less than said drive shaft.

2. In a grading machine having a traveling frame, a draw bar attached to and drawn by 25 said frame, a circle rotative in either direction on said draw bar and provided with a peripheral arcuate row of gear teeth, and a scraper attached to and revoluble with said circle, in combination with a motor on said draw bar and having a drive shaft provided with a worm 30 operatively engaged with said teeth, and liquid supply means for said motor by which pressure liquid can be caused to operate said drive shaft rotating means to rotate said drive shaft, and through it 35 said circle, in either direction, or hold said drive shaft and circle from rotation.

ALBERT R. HENRY.

MARION C. WILLS.
